Primary Examiner — Robin V Webster(74) *Attorney, Agent, or Firm* — Michael J. Feigin, Esq.; Feigin and Fridman(57) **CLAIM**

The ornamental design for a distillation head, as shown and described.

DESCRIPTION

FIG. 1 shows a top and side perspective view of a distillation head.

FIG. 2 shows a bottom and reverse side perspective view thereof.

FIG. 3 shows a side view, the reverse side being a mirror image thereof.

FIG. 4 shows a front view thereof.

FIG. 5 shows a rear view thereof.

FIG. 6 shows a top plan view thereof.

FIG. 7 shows a bottom plan view thereof; and,

FIG. 8 shows a cutaway view taken along line 8-8 in FIG. 5.

The broken line showing is included for the purpose of illustrating environment and forms no part of the claimed design.

The distillation head is shown with a break to indicate non-specified length. The appearance of any portion of the article between the break lines forms no part of the claimed design.

1 Claim, 6 Drawing Sheets(56)
